FOLDABLE STEERING ASSEMBLY

John T. Le Rose, 61 Joseph St.,
Iowa City, Iowa 52240

Filed Mar. 8, 1965, Ser. No. 84,144

Term of patent 7 years

(Cl. D14—30)

FIGURE 1 is a top plan view of a foldable steering assembly showing my new design;

FIGURE 2 is a side elevational view thereof;

FIGURE 3 is a front elevational view thereof;

FIGURE 4 is a perspective view thereof, in closed condition;

FIGURE 5 is a perspective view thereof, the sheath being in extended condition;

FIGURE 6 is a perspective view thereof, the sheath being open;

FIGURE 7 is a perspective view thereof, the handles being in extended condition;

FIGURE 8 is a perspective view thereof, the handles being open; and

FIGURE 9 is a perspective view thereof, the handles being open and the sheath closed, as disclosed in FIGS. 1 through 3.

I claim:

The ornamental design for a foldable steering assembly, as shown and described.
